UNITED STATES PATENT OFFICE

2,453,828

TORPEDO

Louis J. Barry and William S. Hegamyer, Middletown, R. I., assignors to the United States of America as represented by the Secretary of the Navy

Application April 8, 1925, Serial No. 21,706

17 Claims. (Cl. 114—24)

1

This invention relates to improvements in torpedoes and more particularly to mechanism whereby the torpedo may be given any desired irregular course.

Heretofore, for the most part, naval torpedoes have been equipped with means for maintaining them on a substantially straight course throughout their entire run although in some cases mechanisms have been provided for causing the torpedo to circle at the end of any desired distance.

This latter mechanism usually consists in means for locking the steering rudder in hard over right or left position as desired, thereby eliminating the automatic gyro steering control mechanism.

The present invention contemplates more particularly a mechanism for throwing out the gyro control steering mechanism at any desired point causing the torpedo to turn and travel at any desired angle for a predetermined time after which the gyro control steering mechanism may be again restored thus causing the torpedo to zigzag or follow any predetermined revolution.

One of the objects of the present invention is, therefore, to provide a simple and practical mechanism adapted to cooperate with the vertical steering mechanism for causing the torpedo to follow any predetermined course as desired according to a predetermined setting.

A further object is to provide a small compact mechanism which may be directly associated with the vertical steering mechanism without undue increase in weight and space.

A further object is to provide a mechanism of the above character which will be reliable and efficient in use and operation.

Other objects will be in part obvious and in part hereinafter pointed out in connection with the accompanying sheets of drawings illustrating one of various possible embodiments of the present invention and in the several views of which corresponding parts are indicated by similar reference characters.

In these drawings,

Figure 1 is an assembly view showing such parts of the associated steering mechanism and control mechanism in a torpedo as is necessary to understand the same.

Figure 2 is an elevational view with certain parts broken away of the important parts shown in Figure 1.

Figure 3 is an enlarged detail sectional view of the control mechanism.

Figure 4 is a detailed sectional view of the gyro

valve mechanism shown at the top of Figure 3.

Figure 5 is an elevational view taken at right angles to Figure 3.

Figure 6 is an enlarged detail view taken from the opposite side of Figure 3.

Figure 7 is a detailed sectional view taken on the line 1—7, Figure 6.

Figure 8 is a detailed view of the setting mechanism at the bottom of Figure 3.

Figure 9 is a detailed elevational view of the parts shown in Figure 7.

Figure 10 is a detailed view of gyro cam plate.

Figure 11 is a detailed sectional view of the upper part of the reel case.

Figures 12 and 13 are detailed sectional views on the lines 11—11 and 12—12 of Figure 11.

Figure 14 is an enlarged detail view of the control tape.

Figure 15 is a series of similar views showing different parts of the tape.

Figures 16, 17 and 18 are detailed diagrammatic views showing the different figures traversed by the torpedo.

Referring now to the drawings in detail and more particularly to Figures 1 and 2, there is indicated at 20 the supporting frame or unit adapted to carry the gyro pot and certain parts of the vertical and horizontal steering mechanism normally controlling the depth and direction of travel of the torpedo. On this fitting 20 there is mounted two depth spring casings 21, the depth control engine 22, the gyro pot 23 and pallet 24. These parts are of well-known construction and require no detailed description in that they form no part of the present invention except that they may hereinafter enter into certain combinations and are merely designated to show the relative location and position of the figure run mechanism hereinafter described.

Mounted upon the fitting 20 is a main gear 25 which is adapted to be driven by a gear directly associated with the main propeller shaft. This gear 25 is mounted on a shaft 26 which extends towards the left and carries a bevel gear 27 meshing with a gear 28 on the shaft 30 carrying the pinion 31 at its lower end. This pinion meshes with a second pinion 32 to form a gear reduction. The lower part of shaft 33 upon which pinion 32 is mounted is provided with a worm 34 meshing with gear 35 on shaft 36 forming a second gear reduction. On Fig. 5 the shaft 36 carries a worm 37 at its opposite end meshing with a gear 38, Figure 3, upon a shaft 40 carrying at its end a clutch 41 cooperating with a driven clutch base 42. These clutch members are nor-

45

50

mainly urged into engagement by means of a spring 43.

The driving clutch member 41 is provided with a collar 44 engaged by a bifurcated arm 45 of a bell crank lever 46, the end of which lever engages a collar 47 adapted to be moved upwardly by the setting mechanism shown at the bottom of Figure 3 and as will be hereinafter more fully described. This releases the clutch faces whereby the tape carried within the casing 49 may be set to any desired point.

The driven clutch member is provided with an enlarged gear 48 meshing with a tape timing sprocket gear 50 carried by an arm 51 and carrying a reel driving gear 52 as well as the timing sprocket 53 shown more clearly in Figures 6 and 7. This sprocket 53 is adapted to engage a series of perforations 54 in tape 55 whereby it is fed from reel 56, Figure 5, downwardly onto reel 57 within the reel case 49 as shown in Figure 5. The tape 55 is also provided with a second row of perforations 58 formed in any desired pattern or alignment as shown more clearly in Figures 13 and 14 which determines the course of the torpedo. This row of perforations is engaged by a spur wheel 60 carried at one end of an arm 61 pivoted to a fixed support at 62. Thus as the tape is fed the projections on the spur wheel 60 will follow the path of perforations 58 causing the lever 61 to oscillate and thereby move the opposite end 63 in and out with respect to valve casing 64. The end 63 fits between two knurled collars 65 mounted upon valve sleeve 66, the relation of these parts being more clearly shown in Figures 5 and 6.

The valve itself is shown in Figure 4 and comprises the valve shaft 71 of general cylindrical shape provided with enlargements 67-68 and 70 tightly fitting within a sleeve 66 which in turn fits within the valve block 72. The member 71 is provided with a longitudinal passageway 73 and port openings 74, 75 and 76. The sleeve 66 is provided with an inlet port 77 and two outlet ports 78 and 80. The valve member 71 is normally under the control of the gyro pallet mechanism, that is, it is reciprocated according to the relative position of the pallet thereby to permit air entering the port 77 through openings 75 thence into opening 74 or 76 communicating with the outlet ports 80 or 78 respectively according to whether the valve 71 is moved towards the left so as to bring ports 74 and 80 into alignment or to the right so as to bring ports 76 and 78 into alignment. The outgoing air will operate the steering engine to cause a hard-over rudder in one direction or the other according to the port opened. This is substantially the general operation of the steering control mechanism except for the interpositioning of the sleeve 66 which is under control of the pattern Fig. 6 as above described, for it will be seen that as this sleeve is moved to the right, for example, the port 78 in the sleeve will be out of communication with the outlet opening in the valve block and throw this into communication directly with the source of air prior to its entrance through port 77. This will maintain a hardover rudder in that direction until the sleeve is restored to normal position. Likewise if the sleeve is moved in the opposite direction, the air will pass directly out through the opening adjacent port 80 to cause a hardover rudder in the opposite direction.

In this connection reference is made to Figure 10 showing the gyro cam plate 81 with which the pallet mechanism 24 coacts. This cam plate

occupies a position in space similar to that of the gyro and the torpedo body turns relative to this cam plate in describing its figure. This cam plate varies in contour according to the tape with

5 which it is adapted to be used. For convenience of illustration, Figure 10 shows the pallet mechanism as moved relatively to the cam plate, that is, in making angle A (a 150° turn) as shown in Figures 16 and 18, for example, the pallet particularly shifts relative to the cam plate until it reaches the position 82 by which time the tape 55 has progressed so as to bring the perforations 58 controlling the spur gear 60 to actuate the lever 61 and restore the sleeve 66 to the position shown in Figure 4 whereupon the gyro comes into action again and the pallet comes to relative position at rest at point 83 thus maintaining the torpedo on the first reach of its pattern as shown in Figure 16. At the end of a predetermined time the tape again causes an actuation of the lever 61 to throw the sleeve 66 with its ports out of alignment and cause a return curve of the torpedo (movement of 150°) or restore the pallet to the relative position indicated at 24 in Figure 10. This operation is repeated from time to time causing the torpedo to follow the zigzag course as indicated.

30 In Figure 17 there is shown a different form of pattern which may be accomplished by changing the gyro cam plate and tape. The same is true of Figure 18. These patterns are selected according to the maneuver being performed by the enemy fleet, as circumstances may require certain torpedoes being previously equipped and designated to follow certain patterns.

35 The initial run of the torpedo, of course, varies with the range of the target and it is, therefore, necessary to have this variable distance set at will to perform the desired initial torpedo run as indicated in Figure 16 plus an over-run to carry it beyond the line of travel of the fleet with a certain margin of accuracy whereupon the torpedo zigzags back and forth as indicated.

40 In order to accomplish this initial setting, attention is directed particularly to Figure 3 of the drawings wherein is shown a setting shaft 84 extending downwardly through the pedestal 85 supporting the figure run mechanism and terminating in a socket 86 on the under side of the gyro base 20, this base being shown in detail in Figure 8. The setting of this device is accomplished by inserting a square tool in the socket 86 thereby depressing the rod 84 which will disengage a ratchet clutch allowing the tape to be set for operation at any desired point as indicated upon the dial 87 in Figure 8. This setting dial encircles the setting sprocket tube 88 and is connected to it by a system of gears consisting of a spur gear 90, a fixed internal gear 91 and an internal gear 92 cut in the hub of the index dial 87. The internal gear 92 has one more tooth than the internal gear 91 but both mesh with the spur gear 90 which is mounted upon an eccentric on the setting socket shaft 86 as shown in Figure 3. When the setting socket tube is turned through one revolution the spur gear 90 is caused to mesh with the teeth of both gears 91 and 92 and since gear 91 is fixed, gear 90 is caused to move ahead the thickness of one tooth carrying with it the setting dial 87. It will be noted that this dial is divided and marked to correspond with the general lay-out of the tape giving, for example, 15,000 yards straight run before a left figure followed by a right figure is accomplished.

Thus the straight run may be set at will up to the full torpedo range if desired.

When it is desired to set the mechanism for the point at which the figure shall begin, a tool is inserted into the setting socket and the push rod 84 pressed in, carrying with it the collar 47 thereby to move the bell crank lever 46 to disengage the clutch and allow the bevel gears 83 and 84 to turn and advance or set back the tape through the gears 48, 50 and 53, Figure 6. Upon withdrawing the setting tool the spring 43 returns the clutch to engaged position ready for operation when the propeller shaft starts to turn.

Referring now to Figures 11, 12 and 13, showing in detail the internal construction and arrangement of one of the reels carrying the tape, a gear 56 is mounted upon a shaft 95 having keyed thereto a clutch hub 96, with clutch pins 97 within a drum 98 so arranged as to drive the drum when the clutch is rotated in a direction to roll the pins up the incline until they bind and drive the drum as a unit. Since the clutch operates in one direction only, that is, in the direction that it is winding the tape, when the process is reversed during the setting operation this clutch releases and a brake retards the tape to keep it taut. This brake consists of a spring 100 fastened to the drum 104 and presses a pad 102 against the hub 101. As the action of the clutch is very positive and the driving rate of the clutch is sufficient to wind the tape when the diameter of the coil it makes is smallest, a type of slip joint is provided to compensate for the various diameters of the coil as the tape winds. This slip joint consists of four springs 103 which encircle and cling to the rotating drum 104, the springs butt against the key 105 on the reel hub. Since the clutch drives the drum at a constant speed and the reel hub revolves at a various rate, the springs are caused to slip on the drum when the clutch and drums' speed exceed that of the tape reel.

When it is desired to remove the reels the front plate 106 is removed by loosening screws 107, Figure 3, after which the reels and tape may be easily removed from their respective drums. The screw 108 is loosened to carry the support 110 away from the spur gear and timing sprocket 53 as shown more clearly in Figures 2 and 9.

From the above it will be seen that the present invention provides a compact mechanism of reliable, durable and efficient construction which may be easily mounted upon the gyro base plate closely adjacent the pallet mechanism whereby the action of the pallet upon the steering engine is periodically discontinued during the maneuvering of the torpedo according to the design upon the control tape.

The invention is of simple and practical construction and is well adapted to accomplish, among others, all of the objects and advantages herein set forth.

What we claim is:

1. In combination with the gyro and steering engine of a torpedo, a figure run device comprising pattern means for disconnecting the gyro from the steering engine at intervals according to the pattern of said means.

2. In combination with the gyro and steering engine of a torpedo, a figure run device comprising a valve connected with the gyro mechanism for operating the steering engine and pattern means for actuating said valve thereby to disconnect the steering engine from the gyro

at intervals according to the pattern of said means.

3. In combination with the gyro and steering engine of a torpedo, a figure run device comprising a valve connected with the gyro mechanism for operating the steering engine and means for actuating said valve thereby to disconnect the steering engine from the gyro, said means including a perforated tape, means for moving the tape and means actuated by the perforations in the tape for actuating said valve.

4. In combination with the gyro and steering engine of a torpedo, a figure run device, comprising a valve connected with the gyro mechanism for operating the steering engine, a tape having a series of perforations arranged in predetermined pattern, a member engaging said perforations, a pivoted lever carrying said member and moved by change in alignment of said perforations, said lever being connected with said valve for moving the same thereby to connect or disconnect the gyro mechanism from the steering engine according to the pattern.

5. In combination with the gyro and steering engine of a torpedo, a figure run device comprising a valve between the gyro and the steering engine and a supplemental valve sleeve associated therewith adapted to prevent operation of said first valve under predetermined conditions.

6. In combination with the gyro and steering engine of a torpedo, a figure run device comprising a valve between the gyro and the steering engine, a supplemental valve sleeve associated therewith adapted to prevent operation of said first valve under predetermined conditions and means for establishing said predetermined conditions comprising a perforated tape, means for moving said tape and means engaging the perforations in said tape for actuating said supplemental valve sleeve.

7. In combination with the gyro and steering engine of a torpedo, a figure run device comprising a valve interposed between the gyro and the steering engine, a supplemental valve associated therewith adapted to prevent operation of the first valve under predetermined conditions and means for determining said conditions comprising a tape, release upon which said tape is wound, means for driving said release to wind the tape from one to the other and means actuated by said tape for controlling the relative position of said supplemental valve sleeve.

8. In combination with the gyro and steering engine of a torpedo, a figure run device comprising a valve interposed between the gyro and the steering engine, a supplemental valve associated therewith adapted to prevent operation of the first valve under predetermined conditions, means for determining said conditions comprising a tape, release upon which said tape is wound, means for driving said release to wind the tape from one to the other, means actuated by said tape for controlling the relative position of said supplemental valve sleeve and means operable from the exterior of the torpedo for setting said tape thereby to cause an actuation of said supplemental valve at the end of any predetermined initial run.

9. In combination with the gyro and steering engine of a torpedo, a figure run device comprising a casing, two reels within said casing, a perforated tape adapted to be wound from one reel on to the other, means connected with the propelling means of the torpedo for actuating said release, a member engaging the perforations in

said tape, a lever upon which said member is mounted and a sleeve valve actuated by said lever from the steering engine at intervals according to the pattern of the perforations on said tape.

10. In combination with the gyro and steering engine of a torpedo, a figure run device comprising a casing, two reels within said casing, a perforated tape adapted to be wound from one reel on to the other, means connected with the propelling means of the torpedo for actuating said release, a member engaging the perforations in said tape, a lever upon which said member is mounted, a sleeve valve actuated by said lever from the steering engine at intervals according to the pattern of the perforations on said tape and a gyro cam plate associated with the gyro and corresponding in contour to the pattern on said tape comprising two cooperating reels, a perforated tape mounted upon one reel and adapted to be wound on to the other, a train of reduction gears interposed between the propulsion means of the torpedo and said release whereby the latter are driven at a speed proportional to the speed of the torpedo, clutch mechanism associated with said reduction gearing and means for releasing said clutch whereby the tape may be set to function at the end of any predetermined initial run.

11. In combination with the gyro and steering engine of a torpedo, a figure run device comprising a casing, two reels within said casing, a perforated tape adapted to be wound from one reel on to the other, means connected with the propelling means of the torpedo for actuating said reels, a member engaging the perforations in said tape, a lever upon which said member is mounted, a sleeve valve actuated by said lever from the steering engine at intervals according to the pattern of the perforations on said tape, a gyro cam plate associated with the gyro and corresponding in contour to the pattern on said tape, a train of reduction gears interposed between the propulsion means of the torpedo and said reels whereby the latter are driven at a speed proportional to the speed of the torpedo, clutch mechanism associated with said reduction gearing, means for releasing said clutch whereby the tape may be set to function at the end of any predetermined initial run and a valve actuated according to the pattern on said tape and adapted to disconnect the gyro from the steering engine.

12. In combination with the gyro and steering engine of a torpedo, a figure run device comprising a gyro base plate, a casing mounted thereon, reels within said casing, a perforated tape mounted upon said reels, means for feeding said tape from one reel to the other, the perforations in said tape being arranged according to a predetermined pattern, a follower adapted to cooperate with the perforations in said tape, a lever upon which said follower is mounted and a valve connected with said lever adapted to be moved in accordance with the pattern on the tape thereby to connect or disconnect the gyro from the steering engine as and when desired.

13. In combination with the gyro and steering engine of a torpedo, a figure run device comprising a gyro base plate, a casing mounted thereon, reels within said casing, a perforated

tape mounted upon said reels, means for feeding said tape from one reel to the other, the perforating in said tape being arranged according to a predetermined pattern, a follower adapted to cooperate with the perforations in said tape, a lever upon which said follower is mounted and a valve connected with said lever adapted to be moved in accordance with the pattern on the tape thereby to connect or disconnect the gyro from the steering engine as and when desired, said driving means for the reel comprising a chain of reduction gears interposed between the reels and the propulsion means of the torpedo.

14. In combination with the gyro and steering engine of a torpedo, a figure run device comprising a gyro base plate, a casing mounted thereon, reels within said casing, a perforated tape mounted upon said reels, means for feeding said tape from one reel to the other, the perforations in said tape being arranged according to a predetermined pattern, a follower adapted to cooperate with the perforations in said tape, a lever upon which said follower is mounted, a valve connected with said lever adapted to be moved in accordance with the pattern on the tape thereby to connect or disconnect the gyro from the steering engine as and when desired, said driving means for the reel comprising a chain of reduction gears interposed between the reels and the propulsion means of the torpedo and a setting device including a clutch interposed in said reduction gearing whereby the relative position of the tape on said reels may be changed at will to determine the first point of operation of said figure run device.

15. In combination with the gyro and steering engines of a torpedo, a pattern tape, and means operated thereby for disconnecting the gyro from the steering engine at predetermined intervals.

16. In combination with the gyro and steering engines of a torpedo, a pattern tape for deviating the torpedo from its straight line course at definite predetermined intervals and for again returning the torpedo to its straight line course, and means operated by the tape for disconnecting the gyro and steering engines.

17. In combination with the gyro and steering engines of a torpedo, a perforated tape, means controlled thereby for disconnecting said engines from the gyro to successively alter the course of the torpedo.
